UNITED STATES PATENT OFFICE.

HENRY TSCHERNING, OF FREEPORT, ILLINOIS, ASSIGNOR TO ARCADE MANUFACTURING COMPANY, OF FREEPORT, ILLINOIS, A CORPORATION OF ILLINOIS.

CORK-PULLER.

SPECIFICATION forming part of Letters Patent No. 728,519, dated May 19, 1903.

Application filed August 16, 1902. Serial No. 119,848. (No model.)

To all whom it may concern:

Be it known that I, HENRY TSCHERNING, a citizen of the United States of America, residing at Freeport, in the county of Stephenson and State of Illinois, have invented certain new and useful Improvements in Cork-Pullers, of which the following is a specification.

My invention relates to certain new and useful improvements in cork-pullers; and its object is to provide a device of this class which shall be simple, cheap, and effective in operation.

The class of pullers to which my improved puller belongs is the type wherein a cork-screw-carrier and a threaded nut reciprocate in a suitable guideway, the nut and carrier moving together half-way up said guideway, the carrier leaving the nut and moving up along the remainder of the guideway to strip 20 the cork, the carrier and nut then moving down, keeping the same distance apart until the nut reaches the bottom of the guideway, and the carrier then running down to the bottom and screwing into the cork. This is 25 one of several well-known types of pullers, and, as heretofore explained, my improvements are in pullers of this type.

My invention consists more particularly in the devices which are used to cause the cork-screw-carrier and the nut to preserve the proper relative positions—that is to say, the devices which lock them together during the first half of their upward movement permit them to separate during the second half of the upward movement, keep them at a constant distance apart during the first half of the downward movement of the carrier, and permit them to come together during the last half of the downward movement of the carrier. Hitherto the practice has been to use a system of positive locks between the cork-screw-carrier and the threaded nut, two hooks or some similar device being usually used. In my puller I dispense with one of these hooks, replacing the positive lock between the carrier and the nut by a different device, which will be explained in due course.

My invention is fully illustrated in the drawings accompanying this specification and 50 fully described in this specification.

In the aforesaid drawings, Figure 1 is an elevation of the parts of my improved puller, one of the side plates of the case being removed and the nut and corkscrew-carrier being shown in central longitudinal section. In 55 Fig. 1 the parts are shown at the end of the stripping motion. Fig. 2 is a view similar to Fig. 1, all the parts, however, being in elevation except the lower end of the hook on the nut, the parts in this figure being shown just 60 at the beginning of the pulling stroke. Fig. 3 is a vertical section in line 3 3 of Fig. 1 looking in the direction of the arrow. Fig. 4 is a section in the line 4 4 of Fig. 2 looking down. Fig. 5 is a section through the cork-screw-carrier; and Fig. 6 is a front external 65 view of the puller, the case being in position.

In the drawings, A is the case of the cork-puller, made in the usual form from two pieces A' A''. These two pieces are so formed as to 70 leave two openings a a' on the front side of the case, these openings being separated by a stop a''. A longitudinal guideway a³ extends throughout the greater portion of the length of the case. In this guideway runs a nut B, 75 threaded in the usual way to permit the cork-screw to run through it and provided with a lug b, extending into the opening a' and adapted to engage the stop a'' at the upper end of this opening. It is obvious, of course, that 80 the nut is free to move under proper impulse up and down through the guideway, its motion downward being limited by the guideway and movement in the opposite direction being limited by engagement of the lug b 85 with the portion a''. A corkscrew-carrier C runs in the guideway a³ above the nut B, and in this corkscrew-carrier is secured a corkscrew D of the ordinary type, which runs, as heretofore mentioned, through a suitably- 90 threaded portion in the nut B. The corkscrew D is of course rotatable in the corkscrew-carrier C in the usual way. A lever E is pivoted in the case, and this lever is connected by a suitable link e to the corkscrew-carrier C. It is obvious that the movement of the handle E will reciprocate the carrier C. On the nut B is a hook b', adapted to engage a suitable projection c upon the carrier C and lock the nut and corkscrew together during a 100

certain portion of the movement. This hook b' has its upper end pressed toward the path of the carrier by a spring b^2 , confined in a suitable chamber in the bottom of said hook. 5 A pin a^4 , projecting from the interior of the case A, is in the path of a beveled surface b^3 upon the hook b' , and its object is to unlock the hook from the carrier when the nut reaches its upper limit of motion. So much 10 of its operation will be readily understood.

Starting with the nut at the bottom of the guideway and the carrier half-way down the guideway and moving downward, the operation for the first three stages is obvious. The 15 corkscrew-carrier approaches the nut and the corkscrew D is rotated by the threads in the nut B, and thereby forced into the cork. The parts eventually reach the position shown in Fig. 2, when the hook b' latches over the projecting portions c of the carrier C and locks the nut and carrier together. The handle is then moved in the opposite direction and the carrier is raised, dragging the nut with it. The corkscrew, it will be seen, cannot rotate, 20 and it therefore pulls the cork. When the nut reaches its upper limit of motion, its progress is arrested and at the same time the hook b' is released by the pin a^4 and the corkscrew-carrier is free to move on alone, which 25 it does, the corkscrew D being rotated in the reverse direction by the threads in the nut B, thereby stripping the cork from the corkscrew.

The improvement illustrated herein concerns the fourth stage of the motion—that is, the motion from the position shown in Fig. 1 to a position wherein the nut and carrier are the same distance apart, but where the nut is at the bottom of the guideway. In order 30 to insure that the two parts—that is, the nut and the carrier—preserve the proper relation, it hitherto has been customary to provide a lock between these parts which keeps them at the requisite distance. I have discovered, 35 however, that the same thing can be accomplished by preventing the rotation of the corkscrew in the corkscrew-carrier, the positive locking device being thereby dispensed with. I use, therefore, a friction device in 40 the carrier C, bearing upon the head of the corkscrew D. This head is provided with a cylindrical portion d , against which bears a preferably cylindrical block F, pressed toward said corkscrew-head by a coiled spring 45 F', said spring being held in place by a screw-cap F² in the corkscrew-carrier. This cylindrical block exerts sufficient pressure upon the head of the corkscrew to prevent its 50 easy rotation. As a result, therefore, the 55 corkscrew-carrier, corkscrew, and nut are held in the relative positions shown in Fig. 1 until the nut reaches the bottom of the guideway. When that occurs, the tendency of the corkscrew to rotate in the carrier is of course 60 greatly increased, and it overcomes the friction of the cylindrical block. The distinction 65 between the construction herein shown

and the positive lock construction will be quite obvious. In the old form the rotation of the corkscrew in the downward motion was 70 prevented by locking the corkscrew-carrier and nut. In my form the locking of the corkscrew-carrier and nut is effected by preventing the rotation of the corkscrew. The simplicity and desirability of this form will 75 be instantly appreciated.

I realize that considerable changes can be made in the details of construction, and I do not, therefore, desire to limit my invention 80 to the exact construction shown.

I claim as new and desire to secure by Letters Patent—

1. In a device of the class described, the combination with a frame, a corkscrew-carrier and means for reciprocating the same, a 85 corkscrew rotatably secured in said carrier and a nut non-rotatably guided in said frame and threaded to embrace said corkscrew, of means independent of said nut for preventing the rotation of said corkscrew in said 90 corkscrew-carrier, substantially as described.

2. In a device of the class described, the combination with a frame, a corkscrew-carrier and means for reciprocating the same, a corkscrew rotatably secured in said carrier 95 and a nut non-rotatably guided in said frame and threaded to embrace said corkscrew, of means on said corkscrew-carrier for preventing the rotation of said corkscrew in said carrier, substantially as described.

3. In a device of the class described, the combination with a frame, a corkscrew-carrier and means for reciprocating the same, a corkscrew rotatably secured in said carrier and a nut non-rotatably guided in said frame 105 and threaded to embrace said corkscrew, of means for connecting said nut to said carrier during the first portion of the rise of said carrier, means for releasing said nut from said carrier at the beginning of the second part of 110 the rise of said second carrier, a stop to prevent the further rise of said nut, and means independent of said nut for preventing the rotation of said corkscrew in said corkscrew-carrier during a portion of the lowering movement 115 of said carrier, substantially as described.

4. In a device of the class described, the combination with a frame, a corkscrew-carrier and means for reciprocating the same, a 120 corkscrew rotatably secured in said carrier and a nut non-rotatably guided in said frame and threaded to embrace said corkscrew, of means for exerting friction upon said corkscrew to prevent its rotation in said corkscrew-carrier, substantially as described.

5. In a device of the class described, the combination with a frame, a corkscrew-carrier and means for reciprocating the same, a corkscrew rotatably secured in said carrier 130 and a nut non-rotatably guided in said frame and threaded to embrace said corkscrew, of a suitable spring-pressed block movable in said corkscrew-carrier and adapted to exert

a frictional pressure upon said corkscrew to prevent its rotation, substantially as described.

6. In a device of the class described, the combination with a frame, a corkscrew-carrier and means for reciprocating the same, a corkscrew rotatably secured in said carrier and a nut non-rotatably guided in said frame and threaded to embrace said corkscrew, of means independent of said nut for preventing forward revolution on the part of said corkscrew during the first portion of the downward motion of said carrier, substantially as described.

15 7. In a device of the class described, the combination with a frame a corkscrew-car-

rier and means for reciprocating the same, a corkscrew rotatably secured in said carrier and a nut non-rotatably guided in said frame and threaded to embrace said corkscrew, of 20 means on said carrier for preventing forward revolution on the part of said corkscrew during the first portion of the downward motion of said carrier, substantially as described.

In witness whereof I have hereunto set my 25 hand, at Freeport, in the county of Stephenson and State of Illinois, this 28th day of July, A. D. 1902.

HENRY TSCHERNING.
